(57) **CLAIM**

The ornamental design for a tablet computer, as shown and described.

DESCRIPTION

FIG. 1 is a front perspective view of a tablet computer embodying my new design, according to one embodiment; FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of a tablet computer embodying my new design, according to another embodiment;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines shown in the drawings depict portions of the tablet computer that form no part of the claimed design.

1 Claim, 12 Drawing Sheets
